UNITED STATES PATENT OFFICE

JOHN S. GOLDBERG, OF CHICAGO, ILLINOIS, ASSIGNOR TO STROMBERG MOTOR DEVICES COMPANY, OF CHICAGO, ILLINOIS.

CARBURETER.

No. 828,121.

Specification of Letters Patent.

Patented July 13, 1909.

Application filed August 17, 1908. Serial No. 448,767.

To all whom it may concern:

Be it known that I, JOHN S. GOLDBERG, a citizen of the United States, residing at Chicago, in the county of Cook and State of Illinois, have invented a certain new and useful Improvement in Carbureters, (Case No. 14,) of which the following is a full, clear, concise, and exact description, reference being had to the accompanying drawings, forming a part of this specification.

My invention relates to carbureters, particularly to carbureters to be used for controlling the engines of motor vehicles.

The main object of my invention is to provide improved construction and arrangement whereby the range of automobile operation is greatly increased so that the carbureter will respond to all variations in operating conditions of the engine to automatically cause the preparation of the proper gas supply for each condition.

In the operation of gas engines, particularly of automobile gas engines, it is very difficult to keep pace in the carbureter with the suddenly varying conditions of operation, particularly when the engine speed passes through a certain rate and operates at high speed. It is, therefore, the main purpose of my invention to so construct a carbureter that all these operation variations will be kept pace with and quickly provided for, so that the engine will run with equal efficiency at all times and under all conditions.

Generally speaking my invention may be considered as an improvement over the construction shown in my copending application No. 409,696, filed January 7, 1908, and covers improved nozzle construction and improved air inlet arrangement. I provide an elongated nozzle having an outlet at its end and intermediate outlets lying in the apex of a conical air passage-way below these intermediate outlets. An automatically controlled air inlet supplies air to the passage-way at the intermediate outlets and an auxiliary automatic air inlet supplies air to flow across the end of the nozzle. The first automatic air inlet is controlled to be responsive under ordinary conditions of operation and oil is extracted only from intermediate outlets. The auxiliary air inlet becomes responsive when the speed of the engine to be supplied passes beyond a certain rate, at which time oil is also extracted from the

end outlet of the nozzle. The two nozzle outlets and the two automatic air inlet controlling mechanisms coöperate to maintain a uniform and most efficient mixture for the engine.

In the accompanying drawings my invention is clearly illustrated: Figure 1 is a side elevation of the carbureter of my invention, Fig. 2 is a top view of the carbureter with the float valve and controlling mechanism therefor removed, and Fig. 3 is a sectional view taken on line 3—3 of Fig. 2.

The carbureter frame comprises the body part 1, from the lower edge of which extends a shelf 2 which forms the lower wall 70 of the float chamber 3. It is thought unnecessary to describe in detail the construction and arrangement of this float valve mechanism, as it may be exactly the same as that disclosed in my copending application 75 referred to. Forming part of the body part is an outer cylindrical wall or shell 3' through which extends the inner shell 4. The annular base section 5 connects together the lower edges of the walls 3' and 4, the 80 annular chamber 6 being formed between said walls to serve as a heating jacket, and adapted to be connected with a source of heating fluid or gas by means of the outlets 7. The lower section 8 of the inner shell 4 85 is conical, as shown, and converges upwardly, while the upper part 9 of the shell diverges, as shown. A flange 10 extends downwardly from the wall 5 and forms a continuation of the inner shell 4, the passage-way 11 through said inner shell communicating at its lower end with the atmosphere.

Extending diametrically across the lower end of the passage-way 11 is the bridge 12, which has the longitudinal passage-way 13 95 leading from the float controlled oil chamber 3. Interposed in the bridge 12, and axially arranged in the passage-way 11 is the supporting tube 14, which communicates with the passage-way 13. The upper end of 100 this tube has a threaded outlet 15 through which the nozzle 16 threads and extends upwardly. The lower end of the tube 14 is closed by a screw plug 17. Threaded over the lower end of the tube part is the priming 105 cup 18 and the locking nut 19. This priming cup is longitudinally adjustable on the tube 14 so that the upper edge of the cup may be brought varying distances above the level of the lower edge of flange 10. The 110

upper section 16^a of the nozzle is of less diameter than the lower section 16^b, the conical surface 20 between the nozzle sections being in the plane of the inner face of the conical shell section 8. Intermediate outlets 21 from the nozzle interior terminate in said conical area 20, as shown, while the outlet 22 leads from the upper end of the nozzle.

Extending upwardly from above the wall section 3 is the cylindrical wall section 23, forming the throttle passage-way across which extends the shaft 24 supporting the throttle disk 25; to one end of said shaft the throttle lever 26 is secured and may be adjusted and operated in the manner as described in my copending application already referred to. The edge of the part 23 terminates in the connecting flange 27, by means of which the carbureter may be connected 20 with the engine to be supplied.

Extending laterally into the passage-way 11 is the air passage-way 28 formed by the tubular frame 29. This passage-way 28 terminates just above the intermediate outlets 21. An opening 30 in the upper wall of said frame 28 receives the valve seat frame 31, whose lower edge 32 forms a seat for the disk valve 33, which is carried by the valve stem 34, this stem passing through the hub 35 of the frame 31.

Depending from the lower wall of the frame 29 is a sleeve 36 forming a passage-way or pocket 37, concentric with the opening 30. A guide plug 38 screws into the lower end of the stem 34. A spring 39 within the pocket 37 engages the plug 38 and the valve 33 and tends to hold this valve against the seat 32. An adjusting head 40 is secured to the plug 38 and a flange or sleeve 41 extending from said head encircles the sleeve 36 and has longitudinal grooves 42. Also depending from the end of the frame 29 is the arm 43 having at its lower end the threaded opening 44 for receiving the barrel 45 in which is a spring 46 which bears against a detent block 47 in said barrel and tends to hold said block within the grooves 44 to lock the sleeve 41, and therefore, the plug 38 against accidental movement after the spring 39 has been adjusted to give the proper tension for the valve 32. Above the frame 29 another frame 48 extends laterally and forms a passage-way 49 communicating with the upper end of 55 passage-way 11. An opening 50 in the top of said frame 48 receives the valve frame 51 forming at its lower edge a valve seat 52 to be engaged by the disk valve 53, which is carried at the lower end of the valve stem 54. The frame 51 has a central hub 55 through which the stem is guided, and this hub is threaded to receive the nut or sleeve 56 for the horizontal flange head 57 forming one abutment for the spring 58. A nut 59 adjustably threads on the upper end of stem

54 and has a head 60 forming the upper abutment for the spring 58, a cotter pin 61 holding the nut 59 in adjusted position. An arm 62 also extends upwardly from the frame 51 and supports the barrel 63 in which a spring 54 presses against the detent block 65, tending to hold said block in the grooves 66 formed in the sleeve 56 to prevent accidental rotation of said sleeve after adjustment has been made thereof to secure the proper tension of spring 58.

Oil is fed into the float chamber and maintained therein at a constant level, this oil flowing through passage-way 13 into tube 14 and standing in the lower nozzle section at 80 the same level as in the float chamber, this level being indicated by the dotted line 1. If the engine is cold and needs priming, the float mechanism is operated to raise the level for a moment to cause flow of oil through 85 the outlets 21 and into the priming cup 18. The throttle disk being then partly open and the engine cranked, air will be sucked over the edge of the priming cup through the oil therein, then about the edge of the flange 10 and upwardly through the passage-way 11 and into the engine, oil being also drawn from the openings 21 by the air rushing through the passage-way 11, and a very rich starting mixture is then provided. Under 95 ordinary circumstances it will be unnecessary to prime the carbureter, as sufficient oil will be drawn from the openings 21 upon cranking of the engine. The air drawn into the bottom of the passage-way 11 meets the 100 conical converging walls of the section 8 and by the time the air reaches the openings 21, it has attained great velocity and consequently great suction force, and sufficient oil will be drawn from the openings 21 to start 105 the engine and to keep it running efficiently at ordinary speeds. After the air passes the openings and has become saturated with oil, it passes into the diverging part leading to the throttle chamber and expansion occurs 110 in this diverging part, and also more or less agitation of the air and oil so that the oil is thoroughly mixed with the air to cause a rich explosive mixture. At starting, therefore, nearly all the air enters through the 115 bottom of the passage-way 11 and is concentrated on the outlets 21. After the engine, however, picks up speed, the automatic valve 33 becomes operative and air is drawn through passage-way 28 in proportion to the 120 suction created by the engine, and this air meeting the upward stream of air and oil becomes mixed therewith and automatically supplies the proper proportion of air for the explosive mixture, and the amount of air 125 through the automatic valve, of course, varies as the suction effort varies. By adjusting the screw plug 38 and therefore the tension of spring 39, the operation of this automatic valve can be regulated. The up- 130

per section 16^a of the nozzle has the outer threads or baffle extensions 67 in its outer surface, and these assist in breaking up the oil and causing greater agitation of the air 5 and oil. If it were not for these baffle extensions part of the oil drawn through the openings 21 might be drawn along the smooth surface of the nozzle and would not become disintegrated. The automatic valve 33 serves 10 to regulate the air supply for ordinary speeds of the engine, but after the speed reaches a certain rate this valve cannot alone supply the demand for air and consequently the auxiliary valve 53 is provided. The 15 spring 58 controlling the valve 53 is heavier than the spring 37, and, therefore, greater suction is necessary to cause operation of valve 53. However, when the engine reaches a certain rate of speed or generates a certain 20 degree of suction, the spring 58 responds and the valve 53 becomes operative to assist in supplying air to the mixture. The air rushing through passage-way 49 into the throttle chamber passes over the outlet 22 at 25 the nozzle end and assists in drawing oil from the nozzle so that the mixture will have a sufficient oil proportion. By adjusting the head 56 on the hub 55, the tension of the spring 58 and the operation of valve 53 can 30 be regulated. The floors of the frames 28 and 49 slope toward the passage-way 11 so that should any oil, as for instance, oil of condensation reach the chambers 28 or 49, this will immediately flow back into the 35 passage-way 11 and into the path of the air rushing therethrough to be absorbed by said air and turned into gas. Thus for control of the mixture under ordinary speeds, and ordinary conditions of operation of the engine, the nozzle outlets 21 will supply sufficient oil, and the direct air inlet at the bottom of the passage-way 11 and automatic valve 32 will supply sufficient air for the mixture. When the suction of the engine 45 passes a certain limit, then oil will be drawn through the tip outlet 22 of the nozzle and the increased air supply required for this increased oil supply is automatically furnished and controlled by the valve 53. Both 50 the automatic air valves being adjustable, uniformity and efficiency of operation of the carburetor can be controlled to a nicely. After the carburetor is connected with a certain engine permanent adjustment can be 55 made very quickly and then the carburetor will keep pace with all the conditions of operation of the engine and the mixture supplied will be uniform and always at greatest efficiency.

60 It will be noticed that the heating jacket surrounds the entire passage-way 11 and also that the frame 29 passes through the heating jacket, and also that the lower part of the frame 48 is in touch with the heating jacket.

65 The walls near the passageway are therefore

warmed and therefore prevent condensation and disintegration of the gas. The entire frame part of the carburetor, including the base 2 is cast in one piece, thus making a very strong and leak-proof structure.

Changes may, of course, be made in the detailed construction of the various parts, and I do not, therefore, wish to be limited to the exact construction and arrangement shown.

I desire to secure the following claims by Letters Patent:

1. In a carburetor, the combination of a frame forming a passageway open at one end to atmosphere and adapted for connection at its other end with an engine to be supplied, a nozzle extending into such passageway and adapted for connection with a source of oil supply, said nozzle having outlet at an intermediary part thereof and at its 80 end, an auxiliary air inlet near the end of the nozzle, and an additional air inlet near said intermediate outlet, said auxiliary air inlet and said additional air inlet being automatically controlled independently of 85 each other to supply air to the passageway.

2. In a carburetor, the combination of a vertical passage-way open at its lower end to atmosphere and adapted for connection at its other end with an engine to be supplied, a nozzle extending upwardly through said passage-way and adapted for connection with a source of oil supply, said nozzle having a lower outlet and an upper outlet, an air inlet to said passage-way near said lower 95 outlet, a spring controlled check valve controlling the flow of air through said inlet, an auxiliary air inlet near said upper outlet, and a spring-controlled check valve for said auxiliary air inlet.

3. In a carburetor, the combination of a vertical passage-way open at its lower end to atmosphere and adapted for connection at its other end with an engine to be supplied, a nozzle extending upwardly through said passage-way and adapted for connection with a source of oil supply, there being outlet from said nozzle at an intermediate part and at the end thereof, an auxiliary air inlet to said passage-way near said intermediate outlet, a check valve for said auxiliary air inlet controlled by a spring, an additional auxiliary air inlet near the nozzle end, and a check valve in said inlet controlled by a spring, the spring of the additional auxiliary 110 air inlet valve being stronger than the spring of the auxiliary air inlet valve.

4. In a carburetor, the combination of a vertical passage-way, a main air inlet at the lower end of said passage-way, said passage-way being adapted for connection at its upper end with an engine to be supplied, a nozzle extending upwardly through the passage-way and adapted for connection with a source of oil supply, said nozzle having out- 125

let at an intermediate part and at the end thereof, an auxiliary air inlet to the passage-way near said intermediate nozzle outlet, a check valve controlled by the suction at the 5 outlet of the passage-way to admit air through the auxiliary inlet and to the passage-way, an additional auxiliary air inlet to the passage-way near the nozzle end, and a check valve for said additional air inlet 10 also controlled by the suction at the passage-way outlet, greater suction being required to operate the additional inlet check valve than is required to operate the auxiliary inlet valve.

15 5. In a carbureter, the combination of a vertical passage-way having its lower end open to form a main air inlet, a section of the passage-way walls from said air inlet converging upwardly to be conical, the 20 section of the passage-way walls above the conical section being diverging, a nozzle extending upwardly and axially through the passage-way and adapted for connection with a source of oil supply, said nozzle having 25 outlets at its intermediate part near the apex of the converging conical part of the passage-way whereby air flowing upwardly through the conical part will be concentrated to flow with great velocity by such 30 intermediate outlets, said nozzle having also an outlet at its end, an auxiliary air inlet into the diverging part of the passage-way and near the nozzle end, and a valve automatically controlling the flow of air through said 35 inlet in proportion to the suction at the outlet of the passage-way.

6. In a carbureter, the combination of a vertical passage-way having its lower end open to form a main air inlet, a section of 40 the passage-way walls from said air inlet converging upwardly to be conical, the section of the passage-way walls above the conical section being diverging, a nozzle extending upwardly and axially through the 45 passage-way and adapted for connection with a source of oil supply, said nozzle having outlets at an intermediate part thereof near the apex of the converging conical part of the passage-way whereby air flowing upwardly through the conical part will be concentrated to flow with great velocity by such 50 intermediate outlets, an auxiliary air inlet into the passage-way near the intermediate outlets, a valve automatically controlling the flow of air through said auxiliary inlet in proportion to the suction at the passage-way outlet, said nozzle having also outlet at its end, an additional auxiliary air inlet into the diverging part of the passage-way and 55 near the nozzle end, and a valve automatically controlling the flow of air through said additional inlet in proportion to the suction at the passage-way outlet.

7. In a carbureter, the combination of a 60 vertical passage-way having its lower end

open to form a main air inlet, a section of the passage-way walls from said air inlet converging upwardly to be conical, the section of the passage-way walls above the conical section being diverging, a nozzle extending 70 upwardly and axially through the passage-way and adapted for connection with a source of oil supply, said nozzle having outlets at its intermediate part near the apex of the converging conical part of the passage-way whereby air flowing upwardly through the conical part will be concentrated to flow with great velocity by such intermediate outlets, an auxiliary air inlet into the passage-way near the intermediate outlet, a valve 80 automatically controlling the flow of air through said auxiliary inlet in proportion to the suction at the passage-way outlet, said nozzle having also an outlet at its end, an additional auxiliary air inlet into the diverging 85 part of the passage-way and near the nozzle end, and a valve automatically controlling the flow of air through said additional inlet in proportion to the suction at the passage-way outlet, the additional auxiliary air inlet valve being adjusted to require more suction for its operation than the first auxiliary inlet valve.

8. In a carbureter, the combination of a mixing passageway, a fuel nozzle extending 90 into said passageway and provided with zones of outlet openings, and an air inlet at each zone, said air inlets being automatically controlled independently of each other.

9. In a carbureter, the combination of a 100 frame forming a mixing passageway, a fuel nozzle extending into said passageway and provided with zones of outlet openings, an air inlet at each zone, and check valve mechanisms for controlling each inlet, the check 105 valve mechanisms operating independently of each other.

10. In a carbureter, the combination of a frame forming a passageway, a fuel nozzle extending into said passageway and provided with zones of outlet openings, an air inlet at each zone, and check valve mechanism for controlling each inlet, said check valve mechanisms being mechanically independent.

11. In a carbureter, the combination of a frame forming a mixing passageway adapted for connection at its upper end with an engine to be supplied, a fuel nozzle extending upwardly through such passageway and provided with zones of outlet openings, an air inlet to said passageway at each one of said zones, a check valve mechanism for each inlet for controlling the flow of air thereto, the check valve mechanisms being controlled 120 independently of each other by the suction within the passageway, and one of the said valve mechanisms requiring greater suction 125 for its operation than the other.

12. In a carbureter, the combination of a 130

frame forming a mixing passageway adapted for connection at its end with an engine to be supplied, a fuel nozzle extending upwardly through said passageway and provided with zones of outlet openings, an air inlet to said passageway at each zone, spring controlled check valve mechanism for each air inlet, adjusting mechanism for each check valve mechanism for the spring control thereof, said check valve mechanisms being entirely independent of each other.

13. In a carbureter, the combination of a frame forming a vertical mixing passageway open at its lower end to atmosphere and adapted for connection at its upper end with an engine to be supplied, a fuel nozzle ex-

tending upwardly through said passageway and provided with zones of outlet openings, an adjustable main valve at the lower end of said frame for controlling the flow of air 26 into the lower end of said passageway, an auxiliary air inlet to the passageway of each one of said zones, and automatic check valve mechanism for each auxiliary air inlet, said check valve mechanisms operating independently of each other. 25

In witness whereof, I hereunto subscribe my name, this 14th day of August, 1908.

JOHN S. GOLDBERG.
